UNITED STATES PATENT OFFICE

159,873

COMBINATION BOBBY PIN OPENER AND CONTAINER

Nathan L. Solomon, Englewood, N. J.

Application September 15, 1949, Serial No. 5,019

Term of patent 14 years

(Cl. D86—10)

To all whom it may concern:

Be it known that Nathan L. Solomon, a citizen of the United States, residing at 343 Highview Road, Englewood, county of Bergen, and State of New Jersey, has invented a new, original, and ornamental Design for a Combination Bobby Pin Opener and Container, of which the following is a specification, reference being had to the accompanying drawing, forming part thereof.

In the drawing:

Fig. 1 is a perspective view of the combination bobby pin opener and container in a closed condition.

Fig. 2 is a similar perspective view of the combination bobby pin opener and container in an opened condition.

I claim:

The ornamental design for a combination bobby pin opener and container, substantially as shown.
NATHAN L. SOLOMON.
